SIGNALING BY FREQUENCY MODULATION

Application filed July 12, 1927. Serial No. 205,071

This invention relates to frequency modulation and includes a method and means for transmitting and receiving a signal wave over a high frequency carrier wave by slightly changing the frequency and not the amplitude of the carrier wave in accordance with the signal wave.

The increasing traffic of all kinds employing various portions of the available frequency spectrum for the transmission of intelligence makes it desirable that the necessary wave band required for any one channel be greatly reduced. When using amplitude modulation the wave band required for speech telephony extends over twice the width of the useful range of audible frequencies, owing to the resulting side band frequencies. To help narrow this requisite frequency band is the primary object 20 of my invention.

To eliminate fading of radiated signals it has been suggested that the frequency of the transmitted energy be wobbled, and to reduce fading in this manner is a further 25 object of my invention.

I accomplish the aforesaid objects by slightly changing the frequency of the carrier wave at a frequency dependent on the frequency of the signal wave and to an extent dependent on the amplitude of the signal wave, but without appreciably changing the amplitude of the carrier wave at any time. By this frequency modulation, instead of amplitude modulation, I inherently 30 introduce a frequency wobble which helps eliminate fading, and avoid the use of side band frequencies, in the ordinary sense, with their attendant disadvantages.

To change frequency modulation to amplitude modulation it has been suggested that the receiver be detuned. For response to small frequency variation I first heterodyne the received energy to obtain frequency modulated energy of intermediate frequency, and then analyze the intermediate frequency modulated energy by means of a detuned circuit to obtain the signal wave. The requisite maximum wave band may be made as small as desired, since the relative 40 frequency change, for the purpose of analy-

sis, is dependent upon the magnitude of the frequency selected as the intermediate frequency. By this means a range of only five hundred cycles per second, instead of twenty thousand cycles or more, as in the case of amplitude modulation, suffices for successful operation, even on very short wave lengths.

The invention is described more in detail in the following specification which is accompanied by a drawing in which,

Figure 1 indicates a transmitter for frequency modulation;

Figure 2 indicates an alternative form of variable reactance for obtaining frequency change in response to a signal wave;

Figure 3 represents a heterodyne receiver capable of analyzing and translating frequency modulated signals; and

Figure 4 is explanatory of the method of reception.

Referring to Figure 1 there is a micro-wave circuit or other source of a signal wave 2, which may be coupled to a suitable amplifier 4, and then conveyed over a wire 6 for use in obtaining frequency modulation in a transmitter. A high frequency carrier wave is generated in a vacuum tube oscillator 8 having input and output inductances 10 and 12, and a coupling and tuning condenser 14. The anode circuit is energized from a source of direct current 16, which is by-passed for high frequency oscillations by a condenser 18.

In parallel with the tuning condenser 14 there is a variable condenser 20, one plate of which is vibrated by means of an armature 22 which acts under the influence of an electro-magnet 24 which is energized by the energy of the signal wave. It is clear that the magnitude of the frequency variation is determined by the amplitude of movement of the armature 22, and that the effective frequency variation for a given amplitude of movement may be made very small, being governed by the relative magnitude of the two parallel connected condensers 14 and 20, and that for a fixed magnitude of the variable condenser 20 the mean frequency of the 50 55 60 65 70 75 80 85 90 95 100

carrier wave is adjustable by means of the tuning condenser 14.

The frequency modulated output of the oscillator is coupled to a power amplifier 26, the output from which may be conveyed over 5 high frequency lines, or radiated from a suitable antenna 28.

In the foregoing modification the frequency variation was obtained by varying a capacitance, but a variable inductance may equally 10 well be used, in accordance with the modification shown in Figure 2. There the output frequency of the oscillator is determined by a resonant circuit comprising a fixed inductance 42, a tuning condenser 44, and an inductance 46 which is varied by movement of a copper plate 48 located in its flux field. This plate is reciprocated about its pivot 49 by 15 means of an armature 50 which responds to 20 variations in the magnetic field of an electromagnet 52, to which the signal wave is applied.

In case telegraphy signals are to be transmitted an altering current of audible frequency 25 may be keyed, as is indicated by the key 54 controlling the alternator 56. The alternator frequency may be super-audible, in which case any suitable known means may be used at the receiver to render them audible.

A suitable receiver for a frequency modulated carrier wave is indicated in Figure 3, in which carrier energy is picked up in a suitable antenna circuit 60 and is supplied to 35 a super-heterodyne combining tube 62 where it is combined with local oscillations from a local oscillator 64. The intermediate frequency output is fed to an intermediate amplifier 66, which may include several stages 40 of tuned amplification in cascade to accentuate the resonance curve in order to obtain a steep slope on its side. This receiver apparently resembles an ordinary super-heterodyne receiver, but differs in that it must include some means to analyze the frequency 45 modulated energy of intermediate frequency. This is most simply done by tuning the intermediate frequency amplifier 66 to a frequency which lies outside of the operating 50 range of the intermediate frequency.

Thus, referring to Figure 4, the intermediate frequency amplifier is tuned not to the the mean carrier frequency f_m , but rather to a frequency f_r , which is so different from the 55 mean frequency that all of the operating range of intermediate frequency lies to one side of the resonance frequency f_r . This results in an amplitude change in response to the frequency variation, which is rectified in 60 a suitable detector tube 68, the output from which is translated by translating means 70.

It is to be understood that the input circuit of the detector tube 68 may itself be made the analyzing circuit if a less steep resonance 65 curve is required. It is also to be understood

that where the intermediate frequency amplifier is used as the analyzer the tuning need not be done by varying the tuning of the amplifier itself, but instead, its resonance frequency f_r may be left fixed, and the circuits ahead of it may be suitably adjusted so that their frequency difference, the mean value of the intermediate frequency, will equal the relatively detuned frequency f_m .

I consider the use of a preliminary heterodyne desirable in all cases, and essential if slight frequency variation is employed, inasmuch as it increases the frequency variation relative to the frequency of the carrier on which it is impressed, thereby making analysis more practicable. Merely steepening the resonance curve will not solve the problem, for besides the difficulty of constructing exceedingly efficient circuits commercially, it must be remembered that such circuits will 70 tend to average out rather than follow the rapid frequency variations impressed on them.

Having thus described my invention I claim:

1. The method of receiving signals sent by frequency modulation which includes the step of heterodyning the received energy with energy of constant frequency to obtain frequency modulated energy of intermediate frequency in order to increase the degree of frequency modulation of the intermediate frequency energy relative to the degree of modulation of the incoming signal energy whereby analysis and detection of the signal is facilitated.

2. The method of receiving signals sent by frequency modulation which includes heterodyning the received energy to obtain frequency modulated energy of intermediate frequency of augmented modulation relative to the signals sent by frequency modulation, analyzing and rectifying the intermediate frequency energy of augmented modulation, and translating the rectified energy.

3. The method of receiving signals sent by frequency modulation which includes heterodyning the received wave to obtain an intermediate frequency modulated wave of relatively augmented modulation, amplifying the intermediate frequency wave in a resonant circuit tuned to a frequency which lies outside of the operating or modulation range of the intermediate frequency, rectifying the amplified energy, and translating the rectified energy.

4. A receiver for frequency modulated signals comprising means to heterodyne the received energy to obtain energy of intermediate frequency of relatively augmented frequency modulation, an analyzing circuit tuned to a frequency outside of the operating or modulation range of intermediate frequency, and signal translating means.

5. A receiver for frequency modulated sig-

nals comprising a source of local oscillations of constant frequency and a combining device to heterodyne a received frequency modulated wave to a wave of intermediate frequency of relatively augmented frequency modulation, a resonant intermediate frequency amplifier tuned to a frequency outside of the operating or modulation range of intermediate frequency, means to rectify the amplified energy, and means to translate the rectified energy.
